(57) **ABSTRACT**

A fuel regulator includes a limit cap which is attached to a needle valve which is inserted into a regulation hole. In an inner peripheral surface of a second hole portion of the regulation hole, a restriction groove and a guide groove which extends from the restriction groove through an outer surface of a main body portion in an axial direction of the second hole portion are formed. A projecting portion which is inserted into the restriction groove is formed on an outer peripheral surface of the limit cap, and the projecting portion is capable of passing through the guide groove, and in the main body portion, a cast hole which extends from the restriction groove through the outer surface of the main body portion in a direction intersecting the axial direction of the second hole portion is formed.

FIG. 4

FIG. 5

FIG. 6FIG. 7

1
FUEL REGULATOR

BACKGROUND OF THE INVENTION

Field of the Invention

The present invention relates to a fuel regulator for use in regulating an air-fuel ratio of an air-fuel mixture.

Description of the Related Art

Fuel regulating devices which are carburetors of internal combustion engines are equipped with fuel regulators for regulating the air-fuel ratios of the air-fuel mixtures. A fuel regulator includes: a main body portion in which a regulation hole communicating with a flow passage of a carburetor is formed; a needle valve which is screwed into a thread groove in the regulation hole; and a limit cap which is fitted onto the needle valve. Then, the needle valve and the limit cap are engaged with each other in a circumferential direction, so that the needle valve and the limit cap rotate in conjunction with each other.

In the above-described fuel regulator, by rotating the needle valve around the axis to adjust the amount of protrusion of the needle valve into the flow passage, it is possible to increase or decrease the flow rate of a fuel flowing through the flow passage.

In addition, a projecting portion is formed on an outer peripheral surface of the limit cap, and this projecting portion is inserted into a restriction groove formed in an inner peripheral surface of a regulation hole. Then, the movement of the projecting portion is restricted by the restriction groove, so that the rotation of the needle valve is restricted.

When the main body portion of the above-described fuel regulator is cast, a casting mold for forming the regulation hole is removed in an axial direction of the regulation hole. At this time, a groove portion having the same width as that of the restriction groove is formed from the restriction groove through an outer end edge of the regulation hole. That is, the diameter of an outer end portion of the regulation hole is increased.

Note that in the fuel regulator, it is necessary to reduce the size of a gap between an inner peripheral surface of an outer end portion of the regulation hole and an outer peripheral surface of the limit cap in order that the limit cap cannot be pulled off the regulation hole without using a special tool.

In view of this, as a conventional fuel regulator, there is one in which the size of the gap around the limit cap is reduced by fitting an annular guide member into the outer end portion of the regulation hole after the regulation hole is cast (see, for example, Patent Literature 1).

PRIOR ART DOCUMENT(S)

Patent Literature(s)

Patent Literature 1: JP2021-085373A

SUMMARY OF THE INVENTION

In the configuration in which a guide member is fitted into an outer end portion of a regulation hole as in the above-described conventional fuel regulator, there is a problem that since the inner diameter of the regulation hole is increased, the size of the main body portion is increased. In addition,

2

the above-described conventional fuel regulator has a problem that the number of components is increased, and the assembly time is increased.

An object of the present invention is to provide a fuel regulator that solves the above-described problems and makes it possible to compactly form the main body portion, and to reduce the number of components and to thus reduce the assembly time.

In order to achieve the above-described object, the present

10 invention is a fuel regulator comprising: a main body portion in which a regulation hole communicating with a flow passage of a fuel regulating device is formed; a needle valve which is inserted into the regulation hole; and a limit cap which is attached to the needle valve. In the regulation hole, 15 a first hole portion which communicates with a flow passage of the main body portion, and a second hole portion which is open in an outer surface of the main body portion are formed. In the needle valve, a first shaft portion which is screwed into the first hole portion, and a second shaft portion 20 which is housed inside the second hole portion are formed. The second shaft portion and the limit cap fitted onto the second shaft portion are configured to be engaged with each other in a circumferential direction of the limit cap. In an inner peripheral surface of the second hole portion, a restriction 25 groove for rotation restriction, and a guide groove which extends from the restriction groove through the outer surface of the main body portion in an axial direction of the second hole portion are formed. A projecting portion which is inserted into the restriction groove is formed on an outer 30 peripheral surface of the limit cap, and the projecting portion is capable of passing through the guide groove. In the main body portion, a cast hole which extends from the restriction groove through the outer surface of the main body portion in a direction intersecting the axial direction of the second hole portion is formed.

35 In the fuel regulator of the present invention, the cast hole formed in the main body portion is formed when a casting mold for forming the restriction groove in the inner peripheral surface of the second hole portion is removed from the 40 main body portion in the direction intersecting the axial direction of the second hole portion.

45 In the fuel regulator of the present invention, since the restriction groove is formed in the inner peripheral surface of the regulation hole, there is no need to form a large inner diameter of the outer end portion of the regulation hole. Hence, it is possible to reduce the size of the gap between the inner peripheral surface of the outer end portion of the regulation hole and the outer peripheral surface of the limit cap without attaching any component to the outer end 50 portion of the regulation hole. This makes it possible, in the fuel regulator of the present invention, to compactly form the main body portion, and to reduce the number of components and to thus reduce the assembly time.

55 BRIEF DESCRIPTION OF THE DRAWINGS

FIG. 1 is a perspective view showing a fuel regulating device according to an embodiment of the present invention.

60 FIG. 2 is a sectional side view showing a protruding portion of the fuel regulating device according to the embodiment of the present invention.

65 FIG. 3 is an exploded perspective view showing the fuel regulating device according to the embodiment of the present invention.

66 FIG. 4 is a sectional perspective view showing a limit cap of a flow control restrictor according to the embodiment of the present invention.

FIG. 5 is a sectional view taken along a line V-V in FIG. 1, showing the fuel regulating device according to the embodiment of the present invention.

FIG. 6 is a front view showing a regulation hole of the fuel regulating device according to the embodiment of the present invention.

FIG. 7 is a bottom view showing the protruding portion of the fuel regulating device according to the embodiment of the present invention.

DETAILED DESCRIPTION OF THE EMBODIMENTS

An example of an embodiment of the present invention is described in detail with reference to the drawings as appropriate.

A fuel regulator 2 of the present embodiment is used in a fuel regulating device 1 as shown in FIG. 1. The fuel regulating device 1 of the present embodiment is a carburetor (an intake device) of an internal combustion engine of a small-sized working machine such as a chainsaw or a blower, for example.

The fuel regulator 2 includes: a main body portion 10; and flow control restrictors 3 attached into regulation holes 12 formed in the main body portion 10.

The main body portion 10 is a single member which is made of metal and formed by casting. Inside the main body portion 10, a flow passage (not shown) for generating an air-fuel mixture of a fuel and air is formed.

In a front-end surface of a protruding portion 11 formed on a front surface of the main body portion 10, two regulation holes 12 and 12 are open. The regulation holes 12 and 12 are arranged side by side in a lateral direction. Each regulation hole 12 is a through-hole which communicates with the flow passage through which the fuel flows.

In the main body portion 10 of the present embodiment, the regulation hole 12 disposed on the left side of FIG. 6 is a hole portion for regulating an air-fuel ratio of an air-fuel mixture when an output shaft of the internal combustion engine rotates at a low speed. In addition, the regulation hole 12 disposed on the right side of FIG. 6 is a hole portion for regulating the air-fuel ratio of the air-fuel mixture when the output shaft of the internal combustion engine rotates at a high speed. Note that FIG. 6 shows a state in which the flow control restrictors 3 (see FIG. 3) which are described later are removed from inside the regulation holes 12.

In the present embodiment, the configurations of the regulation holes 12 and 12 as well as the two flow control restrictors 3 and 3 attached respectively into the regulation holes 12 and 12 are the same. Hence, in the following description, the regulation hole 12 disposed on the left side of FIG. 6 and the flow control restrictor 3 attached into the regulation hole 12 are described, and the description of the regulation hole 12 disposed on the right side of FIG. 6 and the flow control restrictor 3 attached into the regulation hole 12 is omitted.

As shown in FIG. 2, a first hole portion 13 is formed in a portion on the inner end side of the regulation hole 12 (on the flow passage side of the main body portion 10), and a second hole portion 14 is formed in a portion on the outer end side of the regulation hole 12 (on the front end side of the protruding portion 11).

The first hole portion 13 is a hole portion which has a circular cross section and communicates with the flow passage inside the main body portion 10 (see FIG. 5). In an inner peripheral surface of the first hole portion 13, a thread groove is formed.

The second hole portion 14 is a hole portion having a larger diameter than that of the first hole portion 13 and is open in the front-end surface of the protruding portion 11. In a bottom surface of the second hole portion 14, the first hole portion 13 is open.

Note that in the present embodiment, as shown in FIG. 6, side portions of the respective second hole portions 14 and 14 of the two regulation holes 12 and 12 are joined, so that the second hole portions 14 and 14 form a single hole portion.

In an inner peripheral surface of the second hole portion 14, a restriction groove 15 is formed in an intermediate portion in an axial direction. The restriction groove 15 is a portion recessed in the inner peripheral surface of the second hole portion 14 and extends in a circumferential direction of the second hole portion 14, as shown in FIG. 5. The restriction groove 15 of the present embodiment is formed within an angle range of substantially 90 degrees in the circumferential direction of the regulation hole 12 about the central axis of the regulation hole 12 as a central point.

In the present embodiment, a cast hole 16 penetrates from the restriction groove 15 through the bottom surface of the main body portion 10 (see FIG. 7). The cast hole 16 linearly extends in a direction intersecting the axial direction of the second hole portion 14 (the regulation hole 12).

The cast hole 16 is a hole portion that is naturally formed when the main body portion 10 is cast. At the time of casting the main body portion 10, a casting mold that extends from the second hole portion 14 in the direction intersecting the axial direction of the second hole portion 14 is disposed. By removing this casting mold in the direction intersecting the axial direction of the second hole portion 14, the restriction groove 15 is formed in the inner peripheral surface of the second hole portion 14. At this time, the cast hole 16 is formed from the restriction groove 15 through the bottom surface of the main body portion 10.

Note that in a case where the casting mold for forming the restriction groove 15 is removed in the axial direction of the second hole portion 14, a groove portion having the same width as that of the restriction groove 15 is formed from the restriction groove 15 through an outer end edge of the second hole portion 14. That is, the diameter of an outer end portion of the second hole portion 14 is increased.

In contrast, in the present embodiment, by removing the casting mold for forming the restriction groove 15 in the direction intersecting the axial direction of the second hole portion 14, it is possible to form the restriction groove 15 in an intermediate portion in the axial direction of the inner peripheral surface of the second hole portion 14 without increasing the diameter of the outer end portion of the second hole portion 14 as shown in FIG. 6.

In the inner peripheral surface of the second hole portion 14, a guide groove 17 extending in the axial direction is formed on the outer end side relative to the restriction groove 15 (the front end side of the protruding portion 11) as shown in FIG. 2. An inner end portion of the guide groove 17 communicates with the restriction groove 15, and an outer end portion of the guide groove 17 is open in the front-end surface of the protruding portion 11. The guide groove 17 is a portion through which a projecting portion 61 of a limit cap 60, which is described later, passes when the limit cap 60 is inserted into the regulation hole 12 from outside.

As shown in FIG. 1, the flow control restrictor 3 of the present embodiment includes: a needle valve 30 which is inserted into the regulation hole 12; and the limit cap 60

which is attached to the needle valve 30. The needle valve 30 is a member for regulating an air-fuel ratio of an air-fuel mixture.

As shown in FIG. 3, the needle valve 30 is a linear member having a circular cross section as a whole. As shown in FIG. 2, a first shaft portion 31 is formed in a portion on the inner end side of the needle valve 30 (on the left side of FIG. 2), and a second shaft portion 32 is formed in a portion on the outer end side of the needle valve 30 (on the right side of FIG. 2) (see FIG. 3). The first shaft portion 31 and the second shaft portion 32 of the needle valve 30 are members made of metal.

The first shaft portion 31 is a portion that is disposed on the inner end side of the needle valve 30 (on the left side of FIG. 2) and inserted into the first hole portion 13 of the regulation hole 12 in the state of being attached to the regulation hole 12. In an outer peripheral surface of the first shaft portion 31, a thread groove is formed, and the first shaft portion 31 is screwed into the thread groove formed in the inner peripheral surface of the first hole portion 13.

By rotating the needle valve 30 around the axis to increase or decrease the amount of insertion of the needle valve 30 into the first hole portion 13 and to adjust the amount of protrusion of the needle valve 30 into the flow passage, it is possible to regulate the flow rate of the fuel flowing through the flow passage. In this way, the air-fuel ratio of the air-fuel mixture can be regulated by rotating the needle valve 30 around the axis.

The second shaft portion 32 is a portion that is joined to the first shaft portion 31 and is disposed on the outer-end side relative to the first shaft portion 31 (on the right side of FIG. 2) and housed inside the second hole portion 14 of the regulation hole 12 in the state of being attached to the regulation hole 12. In the front-end surface of the second shaft portion 32, as shown in FIG. 3, a front-end groove 33 for rotating the needle valve 30 around the axis by using a tool such as a screwdriver is formed.

Note that although in the present embodiment, the front-end groove 33 is linearly formed such that a front-end portion of a flathead screwdriver is engaged with the front-end groove 33, the tool for rotating the needle valve 30 is not limited. For example, a cross-shaped groove portion may be formed in the front-end surface of the second shaft portion 32 for a Phillips screwdriver, or a hexagon socket may be formed in the front-end surface of the second shaft portion 32 for a hex wrench.

On an outer peripheral surface of the second shaft portion 32, as shown in FIG. 3, a first projection-and-recess portion 34 is formed over the entire circumference by knurling (linear knurling).

The first projection-and-recess portion 34 is a portion in which a plurality of grooves extending in the axial direction of the needle valve 30 are arranged at equal intervals in the circumferential direction of the second shaft portion 32.

Note that although in the present embodiment, the first projection-and-recess portion 34 is formed on the outer peripheral surface of the second shaft portion 32 by knurling, the method for formation is not limited. For example, the first projection-and-recess portion 34 may be formed by performing cutting, attaching another component, molding, or the like on the second shaft portion 32.

As shown in FIG. 2, on the outer peripheral surface of the second shaft portion 32, a pressed portion 35 which is press-fitted into the limit cap 60 described later is provided on the first shaft portion 31 side relative to the first projection-and-recess portion 34. The pressed portion 35 is an

annular portion which is made of resin and fitted onto the second shaft portion 32 (see FIG. 3).

The pressed portion 35 is molded integrally on the second shaft portion 32 by insert molding. In this way, the needle valve 30 is a single component formed with the first shaft portion 31 and the second shaft portion 32, which are made of metal, and the pressed portion 35, which is made of resin.

The limit cap 60 is a cylindrical member which is made of metal and fitted onto the second shaft portion 32 of the needle valve 30 (see FIG. 3). The limit cap 60 is fitted onto the needle valve 30 and housed inside the second hole portion 14 in the state of being attached to the regulation hole 12.

On an outer peripheral surface of the limit cap 60, as shown in FIG. 3, a projecting portion 61 protrudes. The projecting portion 61 of the present embodiment is formed slightly on the base end side (on the inner end side) relative to a center portion in the axial direction on the outer peripheral surface of the limit cap 60.

On an inner peripheral surface of the limit cap 60, a second projection-and-recess portion 62 is formed over the entire circumference. As shown in FIG. 4, the second projection-and-recess portion 62 is a portion in which a plurality of linear projections 62a extending in the axial direction of the limit cap 60 are arranged in the circumferential direction of the limit cap 60.

In the present embodiment, sets of two projections 62a and 62a are arranged at intervals in the circumferential direction of the limit cap 60. In this configuration, the number of the projections 62a is smaller than in the case where the single projections 62a are arranged at equal intervals in the circumferential direction of the limit cap 60.

As shown in FIG. 2, in the state in which the limit cap 60 is fitted onto the second shaft portion 32 of the needle valve 30, the second projection-and-recess portion 62 of the limit cap 60 and the first projection-and-recess portion 34 of the needle valve 30 are engaged with each other in the circumferential direction of the limit cap 60 and the needle valve 30. This allows the limit cap 60 to rotate around the axis in conjunction with the rotation of the needle valve 30 around the axis.

In the state in which the limit cap 60 is housed inside the second hole portion 14, the entire projecting portion 61 of the limit cap 60 is disposed inside the restriction groove 15.

When the limit cap 60 rotates in the circumferential direction, the projecting portion 61 shown in FIG. 5 comes into contact with an end surface of the restriction groove 15 in the circumferential direction, and hence, the projecting portion 61 is capable of moving around the axis of the regulation hole 12 within a range of a rotation angle of 90 degrees. In this way, the limit cap 60 is capable of rotating by $\frac{1}{4}$ around the axis. In addition, the needle valve 30 on which the limit cap 60 is fitted is also capable of rotating by $\frac{1}{4}$ around the axis.

As shown in FIG. 2, when the limit cap 60 is inserted into the second hole portion 14, the orientation of the limit cap 60 around the axis is adjusted such that the projecting portion 61 passes through the guide groove 17.

Then, in the state in which the limit cap 60 is inserted into the second hole portion 14 and an inner end edge portion of the limit cap 60 is in contact with the bottom surface of the second hole portion 14, the entire projecting portion 61 is disposed inside the restriction groove 15 on the inner side relative to the guide groove 17. At this time, as shown in FIG. 5, the projecting portion 61 is disposed on one end in the circumferential direction in an axial cross section of the restriction groove 15.

In the state in which the limit cap 60 is housed inside the second hole portion 14, the projecting portion 61 is not engaged with the guide groove 17, and the limit cap 60 is thus capable of rotating around the axis inside the second hole portion 14.

In the flow control restrictor 3, as shown in FIG. 2, when the limit cap 60 is fitted onto the second shaft portion 32 of the needle valve 30, the pressed portion 35 of the needle valve 30 is pressed against an inner peripheral surface of the second projection-and-recess portion 62 of the limit cap 60.

The minimum inner diameter of the second projection-and-recess portion 62 (the inner diameter at the apex of each projection 62a) is formed to be smaller than the maximum outer diameter of the pressed portion 35 of the needle valve 30. As the limit cap 60 is fitted from the front-end side of the needle valve 30 to the base-end side thereof, the pressed portion 35 of the needle valve 30 is press-fitted into the second projection-and-recess portion 62 of the limit cap 60. At this time, each projection 62a of the second projection-and-recess portion 62 made of metal bites into the outer peripheral surface of the pressed portion 35 made of resin. That is, the pressed portion 35 is press-fitted and fixed into the second projection-and-recess portion 62 while the outer peripheral surface of the pressed portion 35 is scraped by the apex of each projection 62a of the second projection-and-recess portion 62.

In this way, the needle valve 30 is press-fitted into the limit cap 60, so that the needle valve 30 and the limit cap 60 are fixed in the axial direction.

Next, a procedure for attaching the flow control restrictor 3 to the regulation hole 12 of the fuel regulator 2 shown in FIG. 1 is described.

First, as shown in FIG. 2, the first shaft portion 31 of the needle valve 30 is inserted into the first hole portion 13 of the regulation hole 12, and the thread groove of the first shaft portion 31 is screwed into the thread groove of the first hole portion 13.

Then, by rotating the needle valve 30 around the axis to increase or decrease the amount of insertion of the needle valve 30 into the regulation hole 12 and to adjust the amount of protrusion of the inner end portion of the needle valve 30 into the flow passage, the air-fuel ratio of the air-fuel mixture is regulated.

Thereafter, the limit cap 60 is inserted into the regulation hole 12 from outside. At this time, the projecting portion 61 of the limit cap 60 is caused to pass through the guide groove 17 of the second hole portion 14 of the regulation hole 12.

As the limit cap 60 is moved to the inner end side of the regulation hole 12, the second projection-and-recess portion 62 of the limit cap 60 moves relative to the first projection-and-recess portion 34 of the needle valve 30 in the axial direction and meshes with the first projection-and-recess portion 34 of the needle valve 30. In this way, the second projection-and-recess portion 62 of the limit cap 60 and the first projection-and-recess portion 34 of the needle valve 30 are engaged with each other in the circumferential direction.

In addition, the pressed portion 35 of the needle valve 30 is press-fitted into the second projection-and-recess portion 62 of the limit cap 60, so that the needle valve 30 and the limit cap 60 are fixed to each other in the axial direction.

In the present embodiment, as shown in FIG. 4, since the intervals of the projections 62a of the second projection-and-recess portion 62 of the limit cap 60 is large, the second projection-and-recess portion 62 and the first projection-and-recess portion 34 mesh with each other and are fixed without displacement of the set degree of opening (the position of the needle valve 30 in the circumferential direc-

tion). In this way, even when the pressed portion 35 of the needle valve 30 shown in FIG. 2 is press-fitted into the second projection-and-recess portion 62 of the limit cap 60, the needle valve 30 and the limit cap 60 can be fixed without displacement of the degree of opening.

When the limit cap 60 is attached to the second shaft portion 32 of the needle valve 30 in this way, as shown in FIG. 5, the projecting portion 61 of the limit cap 60 is disposed on one end in the circumferential direction in the axial cross section of the restriction groove 15.

Then, the projecting portion 61 is capable of rotating clockwise (turning right) in FIG. 5 by $\frac{1}{4}$ inside the restriction groove 15 with the state in which the projecting portion 61 is disposed on one end in the circumferential direction in the axial cross section of the restriction groove 15 being as a reference position.

In this way, the limit cap 60 and the needle valve 30 are capable of rotating clockwise (turning right) in FIG. 5 by $\frac{1}{4}$ from the reference position at which the needle valve 30 is attached to the regulation hole 12 to properly regulate the air-fuel ratio of the air-fuel mixture.

The present embodiment is set such that when the needle valve 30 is rotated clockwise in FIG. 5 from the reference position, the flow rate of the fuel passing through the flow passage decreases, so that the concentration of the fuel in the air-fuel mixture decreases.

Since the projecting portion 61 cannot rotate counterclockwise (turn left) in FIG. 5 beyond the reference position due to the restriction groove 15, the needle valve 30 cannot be rotated counterclockwise in FIG. 5 beyond the reference position. In this way, the present embodiment is configured such that the concentration of the fuel in the air-fuel ratio within the movable range of the limit cap 60 is not higher than that in the air-fuel ratio of the air-fuel mixture at the position that is set as the reference position of the needle valve 30.

As shown in FIG. 2, the flow control restrictor 3 as described above includes: the needle valve 30, which is inserted into the regulation hole 12 formed in the main body portion 10 of the fuel regulating device 1, which is a carburetor; and the limit cap 60, which is made of metal and attached to the needle valve 30.

In the needle valve 30, the first shaft portion 31, which is made of metal and screwed into the first hole portion 13 formed on the inner side of the regulation hole 12, and the second shaft portion 32, which is made of metal and housed inside the second hole portion 14 formed on the outer side of the regulation hole 12, are formed.

The first projection-and-recess portion 34 is formed on the outer peripheral surface of the second shaft portion 32, and the pressed portion 35 which is made of resin is provided on the first shaft portion 31 side relative to the first projection-and-recess portion 34 on the outer peripheral surface of the second shaft portion 32. This pressed portion 35 is molded integrally on the second shaft portion 32.

The projecting portion 61, which is inserted into the restriction groove 15 for rotation restriction formed in the inner peripheral surface of the second hole portion 14, is formed on the outer peripheral surface of the limit cap 60. In addition, the second projection-and-recess portion 62, which is engaged with the first projection-and-recess portion 34 of the needle valve 30 in the circumferential direction of the limit cap 60, is formed on the inner peripheral surface of the limit cap 60.

Then, the pressed portion 35 of the needle valve 30 is configured to be pressed against the second projection-and-recess portion 62 on the inner peripheral surface of the limit cap 60.

In the flow control restrictor 3 of the present embodiment, as shown in FIG. 5, the projecting portion 61 of the limit cap 60 is disposed inside the restriction groove 15 of the regulation hole 12 of the main body portion 10, and the movement of the projecting portion 61 is restricted by the restriction groove 15, so that the rotation of the needle valve 30 is restricted. In this way, it is possible to keep the concentration of the fuel in the air-fuel mixture within a proper range.

In the flow control restrictor 3 of the present embodiment, as shown in FIG. 1, the entire front-end portion of the limit cap 60 is open. In this configuration, since the front-end portion of a general-purpose tool such as a screwdriver can be inserted inside from the front end of the limit cap 60 and engaged with the needle valve 30, it is easy to regulate the air-fuel ratio of the air-fuel mixture. In other words, since the opening of the front-end surface of the limit cap 60 is wide, a special tool (for example, one having a tapered front end) is unnecessary. In addition, since the front-end portion of a tool can be easily into the front-end groove 33 of the needle valve 30 with precision, the front-end groove 33 is unlikely to deform.

In the flow control restrictor 3 of the present embodiment, as shown in FIG. 2, since the first projection-and-recess portion 34 of the needle valve 30 and the second projection-and-recess portion 62 of the limit cap 60 are made of metal and unlikely to deform, the needle valve 30 and the limit cap 60 can be engaged with each other at a desired position in the circumferential direction without fail. This makes it possible to prevent the needle valve 30 from rotating around the axis relative to the limit cap 60, and to thus prevent a reference value of the air-fuel ratio of the air-fuel mixture from shifting.

In the flow control restrictor 3 of the present embodiment, since the pressed portion 35 of the needle valve 30 is made of resin, which is more flexible than metal, when the pressed portion 35 is pressed against the second projection-and-recess portion 62 of the limit cap 60, each projection 62a of the second projection-and-recess portion 62 bites into the outer peripheral surface of the pressed portion 35. In the present embodiment, the apex of each projection 62a provided on the inner surface of the limit cap 60, which is made of metal, bites into the outer peripheral surface of the pressed portion 35, which is formed of resin, and is fixed while scraping the pressed portion 35. This makes it possible to fix the limit cap 60 relative to the needle valve 30 in the axial direction without fail, and to thus prevent undesirable rotation.

In the needle valve 30 of the flow control restrictor 3 of the present embodiment, since the first shaft portion 31 and the second shaft portion 32, which are made of metal, and the pressed portion 35, which is made of resin, are integrally molded by insert molding, it is possible to reduce the number of components of the flow control restrictor 3. This can reduce the assembly time for the fuel regulating device 1, and thus can improve the production efficiency.

In the fuel regulator 2 of the present embodiment, the guide groove 17 which extends in the axial direction of the second hole portion 14 is formed from the restriction groove 15 through the outer surface of the main body portion 10 in the inner peripheral surface of the second hole portion 14.

Then, the projecting portion 61 formed on the outer peripheral surface of the limit cap 60 is capable of passing through the guide groove 17.

In addition, in the main body portion 10 of the fuel regulator 2 of the present embodiment, as shown in FIG. 5, the cast hole 16 which extends in the direction intersecting the axial direction of the second hole portion 14 is formed from the restriction groove 15 through the outer surface of the main body portion 10.

10 In such a fuel regulator 2, since the restriction groove 15 is formed in the inner peripheral surface of the regulation hole 12 by removing the casting mold for forming the restriction groove 15 in the direction intersecting the axial direction of the second hole portion 14, there is no need to increase the diameter of the outer end portion of the regulation hole 12.

15 Hence, in the fuel regulator 2 of the present embodiment, it is possible to reduce the size of the gap between the inner peripheral surface of the outer end portion of the regulation hole 12 and the outer peripheral surface of the limit cap 60 without attaching any component to the outer end portion of the regulation hole 12.

20 This makes it possible, in the fuel regulator 2 of the present embodiment, to compactly form the main body portion 10, and to reduce the number of components and to thus reduce the assembly time.

25 In addition, in the fuel regulator 2 of the present embodiment, since the cast hole 16 penetrates from the restriction groove 15 through the bottom surface of the main body portion 10, the cast hole 16 is unlikely to be noticed, and dust is unlikely to enter the cast hole 16.

30 Although the present invention of the present invention has been described so far, the present invention is not limited to the above-described embodiment, and modifications can be made as appropriate without departing from the gist of the present invention.

35 Although in the present embodiment, the fuel regulator 2 and the flow control restrictor 3 used in the fuel regulating device 1, which is a carburetor of an internal combustion engine of a small-sized working machine such as a chainsaw or a blower are described as shown in FIG. 1, devices to which the present invention can be applied are not limited.

40 Although in the present embodiment, as shown in FIG. 5, the projecting portion 61 of the limit cap 60 is capable of rotating inside the restriction groove 15 by $\frac{1}{4}$, the shapes of the projecting portion 61 and the restriction groove 15 or the range within which the projecting portion 61 is capable of rotating are not limited and may be set as appropriate to meet the necessary amount of regulation.

45 50 Although in the present embodiment, the pressed portion 35 made of resin is provided on the needle valve 30, the configurations of the needle valve 30 and the limit cap 60 are not limited. For example, a configuration is possible in which a pressed cylindrical portion made of resin is provided in a part of the limit cap, and the needle valve 30 made of metal is press-fitted into this pressed cylindrical portion.

55 Although the flow rate of the fuel is regulated in the fuel regulator 2 and the flow control restrictor 3 of the present embodiment shown in FIG. 1, the flow rate of the air may be regulated by using the present invention.

60 What is claimed is:

1. A fuel regulator, comprising:
a main body portion in which a regulation hole communicating with a flow passage of a fuel regulating device is formed;
a needle valve which is inserted into the regulation hole;
and

11

a limit cap which is attached to the needle valve, wherein in the regulation hole,

a first hole portion which communicates with a flow passage of the main body portion, and

a second hole portion which is open in an outer surface of the main body portion are formed,

in the needle valve,

a first shaft portion which is screwed into the first hole portion, and

a second shaft portion which is housed inside the second hole portion are formed,

the second shaft portion and the limit cap fitted onto the second shaft portion are configured to be engaged with each other in a circumferential direction of the limit cap,

in an inner peripheral surface of the second hole portion, a restriction groove for rotation restriction, and

5

10

15

12

a guide groove which extends from the restriction groove through the outer surface of the main body portion in an axial direction of the second hole portion are formed,

a projecting portion which is inserted into the restriction groove is formed on an outer peripheral surface of the limit cap, and the projecting portion is capable of passing through the guide groove, and

in the main body portion, a cast hole which extends from the restriction groove through the outer surface of the main body portion in a direction intersecting the axial direction of the second hole portion is formed.

2. The fuel regulator according to claim 1, wherein the cast hole penetrates from the restriction groove to a bottom surface of the main body portion.

3. The fuel regulator according to claim 1, wherein the fuel regulating device is a carburetor.
